UNITED STATES PATENT OFFICE.

JOSEPH L. HERMAN, OF PEORIA, ILLINOIS, ASSIGNOR TO MIDLAND MANUFACTURING COMPANY, OF PEORIA, ILLINOIS, A CORPORATION OF ILLINOIS.

APPARATUS FOR COATING AND TREATING METALLIC MATERIALS.

Application filed June 26, 1925. Serial No. 39,729.

To all whom it may concern:

Be it known that I, JOSEPH L. HERMAN, a citizen of the United States, residing at Peoria, in the county of Peoria and State of Illinois, have invented new and useful Improvements in an Apparatus for Coating and Treating Metallic Materials, of which the following is a specification.

This invention has reference to an apparatus for coating and treating materials having an iron or steel base and particularly the coating and treatment of sheets used for fabricated articles, structures and other purposes.

The invention has for its principal object to provide an apparatus for carrying out the process shown and described in Letters Patent of the United States, issued to me October 3, 1922, No. 1,430,648, for a process of coating and treating materials having an iron base, and being an improvement upon the invention, improvements in an apparatus for coating and treating metallic materials, for which application for Letters Patent of the United States was filed by me April 26, 1923, bearing Serial No. 634,773.

The invention has for a further object an apparatus of the character described, including a heat-treating furnace through which the coated sheets are conducted immediately upon their leaving the molten-bath, and in which the coated sheets are heat-treated; such treatment having for its object to produce a coating more resistant to atmospheric rusting and corroding conditions than for ordinary galvanized sheets and which further will permit a heavier coated sheet to be fabricated without causing the coating to crack or flake off as is the case with heavier coated sheets coated by means of an ordinary galvanized apparatus. The resultant sheet forms a matte surface in contradistinction to the ordinary galvanized sheet which has a spangled surface. The said matte surface is of such a character that it will receive paint, enamel and the like which will firmly attach themselves to the surface as against the necessity for using other means to prepare an ordinary galvanized sheet to receive similar treatment.

A further object of the invention is a galvanizing apparatus, including a heat-treat-

ing furnace adapted for the heat-treatment of sheets immediately upon the sheets leaving the molten-bath, such furnace embodying one or more heat-treating chambers through which the coated sheets are conducted, the sheets being adapted to be heat-treated by means of heat radiated from the walls of the chamber, the fuel employed for heating the furnace comprising oil, gas, or any other well known heating means.

A further object of the invention is a galvanizing apparatus, including a furnace for heat-treating sheets immediately upon their leaving the molten-bath, suitable conducting devices for the sheets being located to conduct the sheets through the heat-treating furnace.

A still further object of the invention is the provision of a heat-treating furnace in a galvanizing apparatus adapted for the heat-treatment of sheets immediately upon their leaving the molten-bath. The ingress and egress openings for the sheets at the front and rear ends of the furnace being reduced to a minimum and constructed so as to practically prevent the infiltration of cold air into the heat-treating chambers of such furnace.

That the invention may be more fully understood, reference is had to the accompanying drawings forming part of this application, illustrating a preferred embodiment of the invention, in which:

Figure 1 is a longitudinally sectional view on a greatly reduced scale partly broken away illustrating an apparatus embodying the invention herein, the sheet galvanizing tank and associated parts being shown in dotted lines and arrows being employed to show the course of the sheets through such tank and heat-treating furnace and also showing the manner in which the heat passes through the heat-treating furnace.

Figure 2 is an end view of one end of the furnace as the same would appear on the line 2-2 Figure 1;

Figure 3 is a cross section as the same would appear on the line 3-3 Figure 1, and;

Figure 4 is a cross section as the same would appear on the line 4-4 Figure 1.

Like characters of reference indicate corresponding parts throughout the figures.

In the drawings and in particular Figure 1 there is illustrated by dotted lines a galvanizing tank 1, such as is commonly used for containing molten zinc used for 5 coating sheets, which is well known to those skilled in this art. Tanks of this character and used for the purposes herein described include at the entrance end of the tank feeding-in rolls 2, at the discharge end of the 10 tank discharging or exit rolls 3 and guiding rolls 4 located within the tank mediate its ends. All such rolls are usually positively driven, although such driving or operating means for the rolls are not shown 15 due to their being commonly and well known in the art.

Adjoining the tank 1 and extending away therefrom at the discharge end thereof and for the purpose of heat-treating the coated 20 sheets as they leave the coating tank, is a heat-treating furnace 5 provided, as shown, with a longitudinally disposed heat-treating chamber 6 through which the coated sheets are conducted and heat-treated. While I 25 have shown only one heat-treating chamber 6 it is understood that it is contemplated that one or more such chambers may be provided, depending upon the scope and use of the invention. The walls of the heat- 30 treating chamber 6, are subjected to heat from the products of combustion formed by the burning of a suitable fuel which finds entrance to the furnace through ports 7, see Figures 1 and 3, on either side of the 35 furnace and which traverses the furnace longitudinally and transversely thereof through the respective passages or flues 8, 10 and 11. Somewhat in the manner shown by the arrows in Figures 1, 3 and 4. Communicating ports 9 are provided at the front 40 and rear ends of the furnace between the flues 8 and 11, and 10 and 11 respectively so as to insure a complete transference of the heat from the products of combustion 45 to the respective walls of the heating chamber 6; the products of combustion finally escaping from the furnace through the stack 12.

13 designates a conveyor or conductor, 50 preferably in the form of a plurality of endless chains which traverse the heating chamber 6 from front to rear, as best seen in Figure 1, and said chains operated by sprocket wheels 14 connected with a shaft 55 15 having secured thereon a gear wheel 16 in mesh with a pinion 17 on a driving shaft 18 provided with a pulley wheel 19 which may be operated by a belt from any suitable 60 source of power. This operating mechanism is located conveniently at the rear end of the furnace and the sheets conducted by the conveyor 13 through the furnace may be discharged from such conveyor 13 on to a cooling rack, not shown. At the forward 65 end of the furnace and at the entrance to

the heating chamber 6 are guiding sprocket wheels 20 on a shaft 21 and at the base of the furnace at the forward end are other guiding sprocket wheels 22 on a shaft 23. It being arranged that the conveyor chains 70 13 traverse the heating chamber from front to rear, thence down and under the furnace and back into the heating chamber, as shown.

Extending forwardly from the heating 75 chamber 6 and in communication therewith is a hood 24 which is curved forwardly and downwardly and preferably with an enlarged mouth which overlies and preferably projects a short distance in to the coating tank 1 in proximity to or in association with the discharging rolls 3 so that the sheets which are coated in the tank and then discharged therefrom by the rolls 3 will be directed upwardly and inwardly through the 80 hood 24 into the heating chamber 6 and on to the conveyor chains 13 which convey such coating sheets through the heat-treating chamber for the heat-treating of such coated sheets. At the rear end of the furnace I 85 provide the hinged gate 25 which normally assumes the closed position shown in Figure 1. This gate and the hood 24 function to restrict and prevent, as far as possible, the infiltration of cold air into the heat- 90 treating chamber so that an approximately uniform temperature may be maintained in said chamber. This object is further attained by the construction of the shield 26 at the forward end of the furnace, which 95 acts as a housing and embraces the meeting ends of the tank and the furnace as shown, up between which the conveyor chains 13 have passage and such shield and hood may be united in any suitable manner, the shield 100 serving as a support for the hood.

The coating tank 1 with the feeding, guiding and discharging rolls, as stated, are not unlike similar structures, and the discharge rolls 3 may be adjusted, although not shown 110 in their relation to each other to determine the thickness of the coating on the sheets and are in no sense used or considered as wipers.

The operation of coating and heat-treating sheets by the apparatus disclosed, it is believed will be thoroughly understood, suffice to say that the sheets are fed or otherwise placed into position to be taken up by the rolls 2 and fed into the coating tank and coated, guided by the rolls 4 and discharged into the hood of the furnace through and by means of the discharged rolls 3, the coating sheets being fed on to the conveyor chains 13 and by the latter conducted through the heating chamber 6 where the coating is heat-treated and such coated and heat-treated sheets discharged from the rear end of the furnace and on to the cooling table referred to. The temperatures em- 125 130

ployed may be one of practice and the furnace may be of any suitable length consistent with the results to be obtained.

What I claim is:—

- 5 1. An apparatus for galvanizing sheets comprising in combination, means for continuously coating the sheets, a furnace for heat-treating the coated sheets, including a heat-treating chamber through which the 10 coated sheets pass as they leave the coating means, a conveying means for carrying the sheets through the furnace and means at either end of the heat-treating chambers for retarding or reducing to a minimum the 15 filtration and circulation of air in said heat-treating chambers.
2. An apparatus for galvanizing sheets comprising in combination, a sheet galvanizing tank, a heat-treating furnace next adjacent the tank, conveying means for conveying the coated sheets through the tank, and means at either end of the furnace for
- retarding or reducing to a minimum the infiltration and circulation of air into said furnace, one of such means including a hood 25 through which the coated sheets pass from the galvanizing tank to the furnace.
3. An apparatus for galvanizing sheets comprising in combination, a galvanizing tank, a heat-treating furnace next adjacent 30 the tank, having a heat-treating chamber through which the coated sheets are conducted, a continuously operated means to conduct the coated sheets through said heat-treating chamber, and a hood forming a continuation of the heat-treating chamber and leading from the receiving end thereof to the discharge point of the galvanizing tank, whereby the coated sheets may be discharged 35 from the galvanizing tank and conveyed to 40 and through the furnace without being exposed to the action of the atmosphere.

JOSEPH L. HERMAN.
